UNITED STATES PATENT OFFICE

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT

PERCOLATOR

Application filed May 26, 1930. Serial No. 455,486.

This invention relates generally to the art of electrically heated cooking utensils, and is more particularly concerned with the structure in which the electrical heating unit of the utensil is mounted.

A typical present day utensil, such as an electric coffee percolator, ordinarily includes a body member and a base member, there being a heating unit carried by the base member which is contained in a recess defined by the wall of the body member.

This invention has in view, as an important object, the provision of a percolator in which the heating unit is housed by a double wall, which is made up of engaging walls of the body and base members and which double wall defines the unit receiving recess. This arrangement presents the advantage of effectively holding the unit against expansion. It also provides for direct heating conductivity from the heating unit to the base so that upon abnormal heating of the unit, some of the heat is conducted to the base and dissipated. Ordinarily substantially all of this heat would go to the body, where it might cause considerable damage to the finish of the device and to the connections between the body and attachments thereto, such as the handle of the percolator.

The invention also contemplates the use of a heating unit of comparatively smaller size so that there is less inherent expansion of the heating unit than has heretofore been the case. This feature, together with the double walled housing of the unit that resists expansion of the unit, prevents, or rather reduces to a minimum, the formation of a space between the heating unit and its housing upon cooling of the unit subsequent to overheating thereof and expansion to abnormal size. In instances where the single wall housing is employed in conjunction with a larger sized heating unit and the latter is overheated, the unit expands to an abnormal size, and subsequent cooling and contraction results in the formation of this space between the heating unit and its confining wall. The efficiency of the heating unit is impaired by this space, which acts

as an insulator, and a very undesirable condition exists. It is this condition which is intended to be obviated by the present invention which provides the double walled structure. Should all the water boil out of the percolator and the device become overheated before the fuse blows, the creation of the space is prevented, or at least reduced, by the double walled structure, which not only holds the unit against expansion, but dissipates the heat to lower the point to which the percolator is overheated.

Other objects will be in part obvious, and in part pointed out more in detail hereinafter.

65

The invention accordingly consists in the features of construction, combination of elements and arrangement of parts as will be exemplified in the construction hereinafter set forth and the scope of the application 70 of which will be indicated in the appended claims.

For a full and more complete understanding of the invention, reference may be had to the following description and accompanying drawing, wherein:

Figure 1 is a side view of the lower part of a percolator in which the heating unit has been mounted in accordance with the present invention. In this view, the percolator is broken away and shown in section to more clearly bring out the mounting of the unit, and

Figure 2 is a somewhat diagrammatic showing developing the interfitting structure 85 of the base and body, which provides the double walled housing for the heating unit.

Referring now to the drawing, the body of a percolator is referred to generally by the reference character A, while the base 90 is designated B. The heating unit which is contained in the base is denoted by the reference character C.

The base B may be provided with any suitable type of supporting means, such as 95 the feet shown at 10. The base B has a curved wall 11 which is part of the exposed surface of the percolator when the parts are assembled, and this wall 11 terminates in a top wall 12. Upstanding from the inner pe- 100

riphery of the top wall 12 is a cylindrical wall 13 that is connected to an upraised wall 14, having a central opening 15, by a curved or conically shaped portion 16. It is the 5 walls 13, 14, and 16 that actually define the recess in which the heating unit C is housed. These walls provide what is, in effect, a central upraised boss that is fitted in a recess in the body member as hereinafter described.

10 The body A is formed with a lower wall structure, which is substantially complementary to the corresponding structure of the base B described in the preceding paragraph. The body A includes an outer wall 17 which 15 cooperates with the wall 11 of the base B to define the exposed contour of the percolator, and this wall 17 terminates in a bottom wall 18 which engages with the top wall 12 when the base B and body A are 20 assembled. A cylindrical wall 19, which finds its counterpart in the wall 13 of the base B, projects upwardly from the wall 18, and is connected to an upraised portion 20 by a conically shaped portion 21. The up- 25 raised portion 20 is formed with an opening 22 which aligns with the opening 15 to provide the opening through which the clamp for the heating unit extends. The central upraised boss on the base B is received in 30 the recess in the body A so that when the parts are assembled, the walls 12, 13, 16, and 14 of the base B closely engage the corresponding walls 18, 19, 21, and 20 of the body A to provide a double walled recess 35 which is referred to generally by the reference character D, and which constitutes a housing for the heating unit C. This heating unit is of the same general type as that shown in the Lamb Patent Number 1,060,263 40 dated April 29, 1913. The latter is positioned in the recess B by a structure including the threaded stem 23 extending through the openings 15 and 22, and a nut 24 which is screwed on the stem 23 and which clamps 45 against the flat wall 20 to cooperate with a flange 25 in positively positioning the heating unit. The stem 23 constitutes a portion of the top radiating member, as in said Lamb Patent No. 1,060,263. The heating unit has 50 a bottom radiating plate 29 provided with a cylindrical peripheral and upstanding flange 30 which snugly fits in the recess D, as shown in Fig. 1. Within the radiating plate or member 29 is located the electrical heat- 55 ing element 31 which consists of a number of superimposed sections with insulating sheets 32 therebetween. This permits of a unit of relatively small diameter, and therefore one having a lesser amount of expansion when heated.

60 By preference, the heating unit is provided with a protective device for breaking the current in the event the utensil reaches a dangerous degree of heat, as when the current is left on after the utensil becomes

empty, or substantially empty. This protective device may be of any suitable sort, but, by way of example, I have shown a protective device in accordance with the disclosure of the patent to Curtiss No. 1,507,587 70 granted September 9th, 1924. The construction and operation of this protective device need not be described here, as they are completely disclosed in said Curtiss patent. 75

The foregoing construction is readily manufactured, and the base and body are easily assembled with the heating unit to provide the finished product. In assembling parts, the circumferential, or cylindrical, 80 walls 13 and 19 are preferably drawn and sized together so that there is a very close intimate contact therebetween, and then the unit is tightly fitted into the recess D so that there is a close intimate contact between 85 the flange 30 and the wall 13; all of which means that the radiating plate, the wall 13, and the wall 19 are in direct conductive relation. In the operation of the device, should all of the water inadvertently boil 90 out, the fuse of the protective device would blow, but the condition may be such that before the fuse blows, the utensil may become overheated. In this event, the extent of 95 overheating of the body is materially reduced, due to the fact that the base B is in direct heat conductivity with the heating unit, and is effective to have heat conducted thereto from the heating unit and which heat is dissipated by radiation from the base. The use of a comparatively small sized heating unit C provides less inherent expansion upon abnormal heating, and this feature, together with the double wall housing which holds the unit against expansion, reduces to 100 a minimum the liability of the creation of a detrimental space between the unit C and the double wall housing which would be detrimental to the efficient operation of the percolator. 105

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. 115

It is also to be understood that the language used in the following claims is intended to cover all of the generic and specific features of the invention herein described and all statements of the scope of the invention which, as a matter of language, might be said to fall therebetween. 120

What is claimed is:

1. In an electrically heated cooking utensil of the character described, and in combination, a body member and a base member, 130

- said base member having a top wall and a cylindrical boss upstanding therefrom and defining a heating unit recess interiorly of the base member, said body member having
- 5 a boss complementary to said first boss, the boss of the base member being snugly fitted in the boss of the body member whereby the cylindrical walls of the bosses are in close and constant intimate contact-
- 10 ing engagement, and a heating unit having a top radiating member, said heating unit also having a bottom radiating member with a cylindrical flange snugly fitted in and in intimate contacting relation with the cy-
- 15 lindrical wall of the boss on the base member, said heating unit also having a heating element interposed between and electrically insulated from said radiating members.
- 20 2. In an electrically heated cooking utensil of the character described, and in combination, a body member and a base member, said base member having a top wall and a boss upstanding therefrom, said boss hav-
- 25 ing a cylindrical wall and a top wall, said body member having a bottom wall formed with a recess having a cylindrical wall and a top wall, said boss being snugly fitted in said recess whereby the cylindrical walls of
- 30 the boss and the recess are in close intimate contacting engagement, a heating unit nested in the recess defined by the boss in the base member and having a top radiating member provided with a stem extending
- 35 through openings in the top walls of said recess and boss, said stem having a flange engaging the underside of the top wall of said boss, said heating unit also having a bottom radiating place provided with a cy-
- 40 lindrical flange snugly fitting in and having close intimate contacting engagement with the cylindrical wall of the boss, said unit also having a heating element interposed between said radiating members, and a nut
- 45 threaded on said stem and between which and said flange the top walls of the recess and boss are securely clamped.
3. In an electrically heated cooking utensil of the character described, and in combination, a body member and a base member,
- 50 said members each having a complementary boss the corresponding walls of which are permanently maintained in intimate heat conducting engagement, a heating unit
- 55 housed within the boss on the base member, and a heat radiating member carried by the heating unit and having a flange maintained in intimate heat conducting engagement with one of the walls of the boss on the base
- 60 member.

JOSEPH F. LAMB.
